SYLVANIA.

INSULATOR-PIN.

1,196,272.

Specification of Letters Patent. Patented Aug. 29, 1916.

Application filed December 18, 1912. Serial No. 737,367.

To all whom it may concern:

Be it known that I, CHARLES L. PEIRCE, Jr., a citizen of the United States, residing in Pittsburgh, county of Allegheny, and State 5 of Pennsylvania, have invented certain new and useful Improvements in Insulator-Pins, of which the following is a specification.

My invention relates to improvements in insulator pins, and more particularly to 10 pins for carrying high tension wires, and which are necessarily of considerable height and subjected to severe stresses.

While the principal object of my invention is to construct an insulator pin that 15 will not break or bend under severe strains, and which will provide a rigid and durable structure, I furthermore seek to provide a pin from which an insulator may be readily removed, and one embodying a structure 20 the parts of which are of minimum weight, are readily set up, and which may be packed for shipment in a small space.

Still a further object of the invention is to provide a pin with a removable base, so 25 that the same pin may be used with bases of various required shapes.

Further advantages of the invention will be more specifically referred to in the description and set forth in the drawings, in 30 which—

Figure 1 is an elevational view of my improved sectional pin with a part broken away and other parts in section; Fig. 2 is a detail sectional view of the top portion 35 of a modified form of pin. Fig. 3 is an elevational view of what I term my single sectional pin with parts broken away and other parts in section. Fig. 4 is a detail sectional view of the top portion of a further modified form of pin.

Referring now more particularly to the drawing, a suitable bolt 4 having a threaded lower end 5 to which a nut 6 is applied, and a head or a threaded or corrugated upper end 7 constitutes the main means for securing the pin to its support and the insulator to the pin. The insulator pin consists, in part, of a metallic shell or truss 8 which is shown in Fig. 3 as consisting of a single 50 piece of sheet metal, which may be either drawn or rolled into cone form or any other suitable shape so as to form a truss, and the upper smaller end of which is provided with threads or corrugations 9.

In the preferred form, the bolt is separably attached to the shell to facilitate packing in a small space for shipment, and to allow the using of bolts of various lengths with the same shell when required by supports of various thicknesses, but it may be 60 welded or otherwise permanently attached thereto.

Obviously an insulator might be cemented or otherwise secured directly to the shell 8 at its corrugated end, and ample strength 65 would be provided in the construction herein described so far, but it is advisable to make provision for quickly removing and replacing the insulator in case of electrical or other injury thereto, and to provide for 70 such removal and replacement separable thimbles adapted to be cemented into the insulator and to be screwed to the pin are advisable. Present types of pins having this separable thimble feature are weak at the 75 joint between the thimble and the main truss or shell, as either the truss only or the securing bolt only extends into the thimble. Frequent breakages occur at this point. In my structure, it will be noticed that both 80 the securing bolt and the shell extend into the thimble and the joint is thereby reinforced. Because of the limited dimensions imposed by general insulator design, this feature is obtainable only by the use of a 85 thimble with thin walls. I provide a thin walled thimble, and at the same time a thimble of the requisite strength and ductility by drawing the same up from flat sheet metal and rolling corrugations 90 therein which provide internal securing threads and corresponding exterior cement-retaining grooves.

As insulator pins are largely used on wood supports, it is desirable that a broad 95 base be provided upon which the shell 8 may rest. It is also desirable to reinforce the lower edge of the shell 8 against spreading under severe strains, and also to retain the bolt 4 in the center of the shell to secure 100 the full benefit of the truss construction. As the wood supports upon which insulator pins are used are made both with flat and convex upper surfaces and of various widths according to the character of the 105 construction, it is essential that insulator pins be furnished with various forms and sizes of bases. To obviate the necessity of

- carrying stocks of complete pins of each desired form, I provide a removable base so that by carrying extra bases only the pins may be assembled to fit the desired support.
- 6 A further important object of the removable base is to facilitate the packing of all the parts of these pins in a minimum of space. A large number of bolts may be packed in one case without waste space. A large number of shells may be nested one within the other into a small space and the bases will likewise pack closely together; allowing the packing of a dozen pins of my design within the space required for three or four pins of usual present types. This feature is of immense importance because of these insulator pins being largely used in unsettled country where transportation is a difficult problem. To this end, therefore, I make the base 13 separate from the shell 8, and provide the same with a retaining annular groove 30, formed by the corrugations 14 and 29, in which groove the lower end of the shell 8 rests. The inner corrugation 14 is higher than the outer corrugation 29 to prevent water seeping into the interior of the shell and running down the bolt hole 17 in the support 16 thereby tending to decay and otherwise injure the support. In Fig. 1 the base 13 is shown adapted for a support with flat top. In Fig. 3 the base 13 shown is for a support with a convex top.
- It is obvious that when desirable, integral connecting means between the lower end of the shell 8 and the base 13 may be provided.
- 40 The securing of the shell to its support will be readily understood by merely stating that when the parts are assembled, by turning upon the nut 6, the upper end of the bolt will be drawn toward the support, thus firmly and rigidly locking the shell upon the base 13.
- 45 The sizes of insulators vary according to the voltage for which they are designed. Insulator pins are therefore also made in various sizes. In Fig. 1, I show a sectional structure whereby pins of various lengths may be assembled by using 1, 2 or 3 shell units. It is obvious that with this structure, a smaller investment in stock will serve to meet the possible demands for pins of different lengths than would be required if a stock of complete pins of each size had to be carried. Yet in this structure none of the essential features of strength, lightness, and facility of packing are lost. In this structure, Fig. 1, the top section 19 is provided with a threaded or corrugated interior for attachment to the bolt 4, while the middle section 20 and the lower section 21 are each slightly reduced in diameter at their closed upper ends, forming annular shoulders 22 and 23 upon which the lower edges of the

sections 19 and 20 respectively rest. When the various sections are drawn together by means of the bolt, a solid structure is thereby provided.

In Fig. 2 I have shown a modified form of construction, which I deem within the scope of my invention, wherein the bolt 4 is provided with an enlarged threaded or corrugated end 24, the lower edge of which forms a shoulder 25 that engages the upper edge of the shell 8. Where a bolt of this construction is employed the upper end of the shell 8 is open and the parts are so proportioned that the shoulder 25 rests upon the upper edge of the smaller end of shell 8 and thus when the bolt is drawn by the nut 6 the shell will be forced against the base plate 13. In this modified form the thimble 26 is provided with sufficient threads or corrugations 27 so as to engage the threads or corrugations on the end 24 and the skirt 28 is made somewhat longer than the skirt 12 in order to provide a greater bearing surface to resist the strain.

In Fig. 4 the bolt 4 is the same as shown in Fig. 2 with the corrugations on the end of the bolt omitted. Corrugations or threads 31 are formed on the shell 8 and complementary corrugations or threads 32 are formed on the lower end of the skirt 28 and the two parts may be secured together by either screwing or cementing.

It is obvious that there are many other ways of securing the shell to the bolt, and, therefore, without confining myself to the particular details of construction herein shown,

I claim:

1. An insulator supporting pin structure comprising a metal truss, a bolt extending through the truss and threaded at its upper end, the upper end of the truss co-operating with the threaded end of the bolt to lock the bolt against downward movement in the truss, and an insulator supporting thimble surrounding the threaded section of the bolt and the upper end of the truss.

2. An insulator supporting pin structure comprising a hollow truss adapted to rest on a support, a bolt extending through the truss and the support on which the truss rests, the upper end of said bolt and truss having direct interlocking connection, and an insulator supporting thimble intimately surrounding the bolt and truss at the interlocking juncture.

3. An insulator supporting pin structure comprising a truss, a bolt, and a thimble for receiving the upper end of the bolt and the truss, said bolt having interlocking engagement with said truss to be held against downward movement therein independently of said thimble, said thimble when applied intimately surrounding said interlocking connection.

4. An insulator supporting pin structure comprising a vertical truss, a bolt, and a thimble for receiving the upper end of the bolt and truss, said bolt having interlocking engagement with the upper end of the truss to hold the truss against downward movement independently of the thimble, said

thimble having threaded engagement with said truss.
